CLAIM

The ornamental design for a cup for beverages or foods, as shown.

DESCRIPTION

FIG. 1 is a front elevational view of a cup for beverages or foods, showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is an exploded top perspective view thereof, where the stirring piece is in an alternate position, fully separated from the cup portion; and,

FIG. 8 is a cross-sectional view thereof, taken along the line VIII—VIII of FIG. 3.
